US0D1052562S

(12) **United States Design Patent** (10) **Patent No.:** **US D1,052,562 S**
(45) **Date of Patent:** **** Nov. 26, 2024**

(54) **RFID TAG INLAY**

(71) Applicant: **SATO HOLDINGS KABUSHIKI KAISHA**, Tokyo (JP)

(72) Inventor: **Yuichi Arao**, Tokyo (JP)

(73) Assignee: **SATO HOLDINGS KABUSHIKI KAISHA**, Tokyo (JP)

(**) Term: **15 Years**

(21) Appl. No.: **29/886,199**

(22) Filed: **Mar. 6, 2023**

(30) **Foreign Application Priority Data**

Sep. 7, 2022 (JP) ..... 2022-019183 D

(51) **LOC (14) Cl.** **14-03**

(52) **U.S. Cl.**

USPC **D14/230**

(58) **Field of Classification Search**

USPC D14/230, 231-240, 238.1, 299, 343, 489,

D14/492, 138, 135; D13/182;

D12/42-43

CPC H01Q 7/00; H01Q 13/10; H01Q 9/285;

H01Q 19/30; H01Q 1/36; H01Q 1/38;

(57) **CLAIM**

The ornamental design for a RFID tag inlay as shown and described.

DESCRIPTION

FIG. 1 is a front elevation view.

FIG. 2 is a rear elevation view thereof.

FIG. 3 is a top plan view thereof.

FIG. 4 is a bottom plan view thereof.

FIG. 5 is a left side elevation view thereof.

FIG. 6 is a right side elevation view thereof; and,

FIG. 7 is front right top perspective view thereof.

The broken lines showing portions of the article form no part of the claimed design.

1 Claim, 4 Drawing Sheets
